UNITED STATES PATENT OFFICE.

MORRIS BREGMAN, OF LEEDS, ENGLAND.

APPAREL APPARATUS.

Application filed February 17, 1920. Serial No. 359,253.

To all whom it may concern:

Be it known that I, MORRIS BREGMAN, a subject of the King of Great Britain and Ireland, residing at Leeds, in the county of York, England, have invented a new and useful Improvement in Apparel Apparatus, of which the following is a specification.

This invention relates to improvements in connection with garment shaping and finishing machines, designed more especially to turn, shape, stretch, and finish pockets, pocket flaps, trousers bottoms, trousers legs, coats, coat sleeves and collars, and waistcoat collars.

The objects of this invention are to provide a pair of upright shafts adjustably spaced apart, to provide means whereby the shafts may be caused to rotate either separately, in either direction or simultaneously in opposite directions, and finally to provide at the upper ends of the shafts adjustable and detachable means whereby the various turning, shaping, stretching and finishing operations can be effected mechanically.

25 Description of accompanying drawings:

Figure 1 is a partial plan of the machine, partly in section and with the greater part of the table cut away.

Figure 2 is a sectional side elevation of 30 the machine.

Figure 3 is an opposite side elevation of part of the machine on a larger scale and with a slightly modified form of adjustment.

Figure 4 is a plan of the detachable and 35 adjustable clamp as employed for turning-up trousers bottoms for pressing or for turning pocket flaps and the like.

Figure 5 is an elevation, and Figure 6 is 40 a plan, of clamp as employed for turning-in coat sleeve linings.

Figure 7 is a plan of the clamp mechanism as adapted and adjusted for turning-up trousers bottoms; and Figure 8 is a plan of the same on completion of this operation.

45 Figure 9 is a plan of the clamp mechanism as adapted and adjusted for turning-in coat sleeve linings; and Figure 10 is a plan of the same on completion of this operation.

50 Figure 11 is a plan of the clamp mechanism as adapted and adjusted for turning-out coats; and Figure 12 is a plan of the same on completion of this operation.

55 Figure 13 is a side elevation of the clamp mechanism as adapted and adjusted for

shaping and stretching coats for pressing; and Figure 14 is a plan of the same.

According to my invention I provide a box or stand A, on which is mounted in sliding guide plates B on opposite sides a pair 60 of upright shafts C, which have a transverse adjustment to and from each other upon the box or stand A by means of a transverse right and left hand screw D, and which have also a rotating movement in opposite 65 directions by means of a right and left hand worm shaft E (hand or power driven) and worm wheels F, these transverse and rotating movements of the upright shafts C being alternative and interchangeable, or si- 70 multaneously operative; or either of the upright shafts C may be arranged to rotate without the other. The box or stand A may have also if desired a longitudinal sliding adjustment upon a baseplate by 75 means of a longitudinal screw G (Figs. 3, 13, and 14).

To permit of the independent disengagement and reengagement of the upright shafts C, the worm wheels F are loose and 80 each shaft is fitted with a sliding clutch H controlled by a pivoted clutch lever I having a locking device J of any convenient type.

The upright shafts C carry at their upper ends detachable pairs of pivoted spring 85 guide clamps K having interchangeable jaws of shapes and sizes suitable for the particular kinds of work to be done, the aforesaid combination of movements enabling the various turning, shaping, stretching, and fin- 90 ishing operations to be effected by these clamps K instead of by hand as hitherto. The jaws are interchangeable by means of slot and stud connections L (Figs. 1, 4, 7, 95 and 8), socket and stud connections M (Figs. 5, 6, 9, and 10), or otherwise, and they may be fitted with spring spreader fingers N to facilitate the opening wide of pockets and the like whilst being reversed and with adjustable gauges O for regulating the depth 100 of turn-up of trousers and the like.

Each clamp K is detachably supported in a small fork P which is pivotally mounted on the upper end of the rotatable upright shaft C. An oblique rising and falling 105 movement is imparted to the jaws of the clamps during their rotation, so as to permit of the clamps passing each other during such rotation. This oblique rising and falling movement is obtained by means of a cam 110

and roller device, the roller Q being carried by the clamp fork P, and the cam R being of an annular form and adjustably supported around a stationary ring S. Or the cam R 5 may be flat, one clamp passing the other at a different level.

Each clamp K is preferably fitted with a self-locking device at its heel end, this device comprising for example a weighted cam 10 lever T pivoted on one side and engaging with a small roller T' on the opposite side. U is a table for supporting the work beneath the clamps K.

The apparatus as previously stated is 15 designed to effect mechanically the various turning, shaping, stretching, and finishing operations appertaining to the production of garments. For example, in turning-up trousers bottoms (Figs. 7 and 8) the trousers 20 leg V, supported on the table U, is gripped at the bottom on opposite sides by the two clamps K (see Fig. 7), the gauges O being first set to the required depth of turn-up, and the upright shafts C with the clamps K 25 are then simultaneously rotated in opposite directions, until on completion of a semi-circular movement the clamps K occupy the position shown in Fig. 8, forming the turn-up W at the bottom of the trousers leg V, 30 which turn-up is pressed before opening the clamps, thereby dispensing with the necessity for basting. For turning-in coat sleeve linings (Figs. 9 and 10), the appropriate clamps K are substituted and the cloth of 35 the sleeve X is pushed in folds into the bows of the clamps (see Fig. 9), the sleeve lining Y resting on the table U; the upright shafts C with the clamps K are then simultaneously rotated in opposite directions, until on completion 40 of a semi-circular movement the clamps occupy the position shown in Fig.

10, with the sleeve lining turned in, and the sleeve bottom Z in position for pressing before opening the clamps. For turning-out coats (Figs. 11 and 12), the appropriate 45 clamps K having forked and shaped ends 1 for the collar are substituted and the coat is pushed in folds on to the clamps, with the arms 2 of the clamps between the cloth and the lining (see Fig. 11); the clamps K are 50 then rotated, until on reaching the position shown in Figure 12 the coat is turned out with the collar 3 in position for pressing before opening the clamps. In each of these cases the spreader fingers N hold the cloth 55 clear of the clamps K as they pass through the opening. For shaping and stretching coats for pressing (Figs. 13 and 14), a shaped block 4 is substituted for the table U to support the garment 5, which is gripped by the 60 clamps K in front at points corresponding to the lower limits of the lapels to be formed; the upright shafts C with the clamps K are then adjusted by means of the screw G to stretch the garment upon the block 4, after 65 which the lapels and collar are turned back against a loose gauge plate 6, in which position they are held for pressing before opening the clamps.

I claim:

1. In a garment shaping and finishing machine, a pair of adjustably spaced upright shafts provided at their upper ends with adjustable and detachable pairs of clamps formed with removable jaws, and means 75 for rotating said shafts separately and simultaneously in a required direction.

2. In a garment shaping and finishing machine as claimed in claim 1, cam and roller mechanism for moving said clamps upwards. 80

MORRIS BREGMAN.
